ART OF PACKAGING AND DISPENSING FLUENT COMMODITIES

Milton M. Karger, Milwaukee, Wis.

Application April 19, 1937, Serial No. 137,710

3 Claims. (Cl. 221—77)

This invention relates to improvements in the art of packaging and dispensing fluent commodities.

A general object of the present invention is to provide an improved method of and means for packaging a fluent commodity in a sealed container and in subsequently providing a discharge opening in the container and manipulating the container in a manner so as to forcibly discharge some of the commodity directly therefrom through the opening in the form of a spray or stream.

A further object of the invention is to provide a method of and means for packaging a fluent commodity in a telescopic container and then subsequently so operating the container, after an opening has been formed therein, to cause some of the commodity to be pumped therefrom, the original container serving as the impelling means.

20 A further object of the invention is to provide a container, generally of paper board construction, which may be readily initially filled or loaded with a fluent commodity and thereafter be subjected to a certain manipulation so as to 25 forcibly eject material directly from the container in the form of a spray or stream, the container being of a character so as to preclude its being refilled, and furthermore being very inexpensive so that it may be discarded after the 30 contents have been discharged therefrom.

As a more specific aspect of the invention, it is contemplated that the present method and container per se are especially adaptable for use in connection with the vending of oil. Recently, 35 oil companies have found it very desirable to vend oil in containers formed of paper board. It is desirable that the paper board container for this purpose have metallic ends, one of which is opened or mutilated for dispensing purposes.

40 Paper board containers of this general type are very advantageous because they are non-refillable and therefore cannot be re-used with a substitute or inferior commodity, are easily disposed of, are cheap, and are light. The major objections, heretofore, to this type of an oil container reside in the fact that oil is very difficult to pack and store because it has great seeping and leaking tendencies, and in this general class of containers, when used for oil, the walls of the 45 containers have been marred and rendered unsightly by virtue of oil soaking through the paper board walls thereof, and also seepage and leakage of oil has been found to occur at the junction of the metal caps with the ends of the paper board body. In addition, due to the fact that the ends 50

of the body of these containers are closed by metal caps which are crimped or clamped into place, the packer must of necessity have special cap applying machinery, which is a draw-back and disadvantage.

With reference to the present invention, it is a more specific object to provide a paper board container especially adapted for the packaging of oil, and overcoming the above objections by virtue of constructional features which eliminate the possibility of oil leakage or seepage, the container furthermore being of such a character that the manufacturer can originally apply the metal caps to the ends of the body portions, and the packer is only required to fill the container and to seal it or close it in a very convenient manner without the necessity of having special equipment or machinery for this purpose.

A further object of the invention is to provide a paper board container especially adapted for the packaging of oil, which meets all of the requirements as to being light, durable, non-refillable, and inexpensive.

20 A further object of the invention is to provide a paper board container of the character described, which after being opened for dispensing purposes may be used in the nature of a pump so as to forcibly eject oil therefrom whereby the 25 contents of the container may be easily and rapidly exhausted.

30 A further object of the invention is to provide a paper board lubricant container which may have interchangeable fittings applied to the discharge end thereof to adapt the container to the forceful dispensing of various types of lubricant directly into the various portions of a motor vehicle, such as the crank case, transmission, or the differential.

35 A further object of the invention is to provide a method of and means for packaging and dispensing a fluent commodity which is very simple, which is inexpensive and expeditious, and which is well adapted for the purposes set forth.

With the above and other objects in view, the invention consists of the improved method of 40 and means for packaging and dispensing fluent commodities, and its parts, combinations, and steps, as set forth in the claims and all equivalents thereof.

45 In the accompanying drawings in which the same reference characters indicate the same parts in all of the views:

Fig. 1 is a perspective view of the improved container just prior to the connection of the container sections to effect a sealed, closed package;

Fig. 2 is an enlarged vertical sectional view of the container in closed, sealed condition;

Fig. 3 is an end view of the container after rupture or mutilation of an end cap for dispensing purposes;

Fig. 4 is an enlarged, fragmentary, detailed sectional view of one end portion of the container showing the telescopic arrangement of the two sections thereof and also showing the manner in which a cap is applied to an end of one of the sections;

Fig. 5 is an enlarged, fragmentary, detailed sectional view of the other end of the container after the seal between the sections has been broken and with a special discharge appliance applied to the ruptured end of the container;

Fig. 6 is a similar view showing another form of appliance fitted on the ruptured or discharge end of the container;

Fig. 7 is a perspective view showing the method of manipulating a modified form of container for the discharge of the contents thereof;

Fig. 8 is a longitudinal sectional view, on a larger scale, of the form of container shown in Fig. 7 in its closed sealed condition;

Fig. 9 is a view of the discharge end thereof after the removal of a temporary closure cap; and

Fig. 10 is a vertical sectional view of the container of Fig. 8, only showing the telescopic movement of the container sections to effect pump action for the discharge of the contents.

Referring now more particularly to the form of the invention shown in Figs. 1 to 6 inclusive, it will appear that the improved container comprises a pair of complementary telescopic sections including an outer section 15 and an inner section 16, both of which are of cylindrical formation with the cylindrical body portions of the same being formed of plied paper board or other suitable fibrous material. The outer end of the section 15 is sealed and closed by means of a dished metallic cap 17 best shown in Figs. 2 and 4. The end wall portion of the tubular section 15 to which the cap 17 is applied, has crimped there-about a U-shaped band or collar 18, and when the cap 17 is applied to said end portion of the body section 15, the peripheral flange 19 of said cap is bent tightly about and into engagement with the collar 18, tightly clamping and embracing the end portion of the section 15. If desired, a soldered connection may be effected between contacting portions of the collar 18 and the cap flange 19.

The outer surface of the cylindrical body of the inner container section 16 has a coating thereon as indicated at 20 in Fig. 4. Said coating is of a character so as to render the wall of the member 16 impervious. The outermost end of the container section 16 is surrounded by a fibrous material collar 21 which is positioned relative to the end of the body section 16 so as to extend somewhat beyond the said end and thereby provide an internal annular shoulder. The end portion of the body section 16 under consideration is tightly embraced by a U-shaped metallic element 22, and the inwardly offset face of a metallic end cap 23 seats firmly against said embracing element 22 and has its peripheral flange 24 bent over and clinched to the projecting end portion of the collar 21 so as to tightly embrace said projecting end portion of the collar. It will thus be noted that said end of the inner telescopic section 16 is thus closed by the metallic cap 23 which is seated on the metal en-

cased shoulder, and the union can be additionally strengthened by a soldered joint, if desired.

The form of container under consideration is especially suited for the packaging and dispensing of oil. The manufacturer of the container will supply the same to the oil packer or vendor in substantially the condition shown in Fig. 1; that is to say, each container will comprise the two complementary telescopic sections 15 and 16 with the outermost ends of the respective sections 10 closed by the metallic caps. The oil vendor or packer merely has to separate the sections 15 and 16 and fill the inner section 16 with the oil or other fluent commodity. Thereafter the container is closed by moving the section 15 onto the section 16 and sliding it lengthwise thereof in a telescopic manner until the uncapped end of the section 15 contacts the inner peripheral shoulder of the collar 21. It should also be observed that the container sections 15 and 16 are so proportioned that when the container is thus closed, the innermost end of the section 16 will abut tightly against the inset wall of the end cap 17, in the manner shown in Fig. 2. When the container is thus closed, it may be sealed in this condition by the application of a sealing medium to the crevice or joint between the open end of the section 15 and the inner periphery of the collar 21, as indicated at 25 in Fig. 2. It is also obvious that the container joint may be sealed or closed by any other convenient means such as tape or the like.

From the description thus far, it will be evident that the container is packed or filled by the packer or vendor in a very simple and expeditious manner, and no special tools or equipment are required for the filling and sealing operations. When the container is thus filled, closed and sealed, it is leak-proof and especially advantageous for the holding and storing of a commodity such as oil. Because of the two-sectional construction of the container there are a multiplicity of plies through which material would have to seep if leakage through the major wall portion should occur, and the characteristics of the walls and the number of plies forming the same precludes this possibility. In addition if the tubular walls are formed with longitudinal seams, the outermost section covers and protects the seam of the inner section. In addition to this the innermost section has the coating or impregnation 20 which guards against leakage or seepage. Leakage or seepage at the ends of the container is protected against by virtue of the constructions of said ends and the manner in which the end caps 17 and 23 are applied. The cap 17 is clinched about the metallic element 18 and the end of the body member 15 is tightly embraced and clamped therein, and in closed condition the end of the inner section 16 tightly abuts against the cap 17 and element 18 and forms a gasket or washer. The same is likewise true of the other end of the container. In this instance the metal cap 23 is applied to the peripheral portion of the collar 21, but it seats on and abuts against the metallic element 22 which in turn clinches the end of the inner section 16.

In the use of the improved container it is contemplated that the vendor, such as a filling station, be supplied with a number of the sealed 70 packages containing lubricants of different classifications. If the motorist desires a certain quantity of a certain type of lubricating oil introduced into the crank case of his vehicle, he will so instruct the attendant, and the proper sealed 75

package will be selected. Thereafter the end cap 23 of the container will be ruptured or cut out to provide an opening 26 therein, as in Fig. 3, and the seal or securing means between the collar 21 and section 15 will be broken. A special appliance 27 (see Fig. 5) with which the attendant is provided, will then be forced over the ruptured end of the section 16, and said appliance 27 includes a cupped portion 28 with overhanging sides which tightly and frictionally embraces outer portions of the collar 21. The outer wall of the cupped member 28 has an opening 29 therein from which extends a section of flexible tubing 30 which carries a nozzle or spout 31 at its outermost end. A funnel structure 32 may be incorporated within the cupped member 28 with its reduced end registering with the opening 29 and the inner end of the flexible tubing 30.

When the appliance 27 is thus positioned on the proper end of the container and the seal is broken, the end of the tubing 30 is introduced into the crank case inlet opening of the vehicle and then the operator holds the container with the section 16 in one hand and the other section 15 in the other hand and reciprocates said sections back and forth telescopically in the manner of a pump and thereby forcibly and quickly ejects all of the contents of the container into the crank case via the tubular connection 30. After the container has been thus emptied, the appliance 27 is removed so as to be subsequently used with other containers, but the emptied container is then discarded and may be readily destroyed. It cannot be refilled or re-used because the metallic end thereof has been ruptured and opened for dispensing purposes.

In Fig. 6 a slightly modified form of appliance 27' is illustrated in its application to the discharge end of the container. This appliance 27' is especially adapted for use in connection with introducing the contents of the container into the differential or a like portion of a vehicle. The appliance 27' has a cupped portion 28' which is frictionally fit onto and over the opened end portion of the container, as shown in Fig. 6. The flat end wall of the appliance 27' has a central discharge opening therein, from which a tubular stub 30' projects outwardly. The outer end of the stub 30' is externally threaded as at 32 to receive the internally threaded inner end of a hook shaped discharge nozzle 31'. In use said nozzle 31' is introduced into the opening into which lubricant is to be forced, and the container is reciprocated back and forth telescopically to pump out the contents through the stub 30' and nozzle 31'. If desired the appliance 27' may be equipped with an air vent 33 which will be located over the rupture 26 in the container end. The orifice 34 in said vent 33 is normally closed by a ball valve 35 to prevent the flow of lubricant therethrough, but said ball valve can move away from the orifice 34 to admit air to facilitate the pumping operations.

A modified form of container is shown in Figs. 7 to 10 inclusive. This form of container is especially adapted for the packaging of fluent commodities of a granular nature wherein the concern regarding leakage and seepage is not acute. Said form of container comprises an outer cylindrical section 15' closed at its outer end by a metallic cap 17' and an inner cylindrical section 16' having its outer end portion surrounded by a collar 21', the outer end of which has clinched thereto a metallic end cap 23' whose inner peripheral portion seats against the

shoulder formed at the end of the tubular section 16'. The sections 15' and 16' are formed of paper board or similar fibrous material, and the cap 23', which forms the discharge end of the container, is provided with an outer circle of relatively small discharge orifices 36 and a central orifice 37 through which air may be admitted.

In use the discharge end 23' of the inner section 16' is covered by a temporary and removable cap 38 (see Fig. 8). The section 16' is then filled with the fluent commodity through its open end, and the package is next closed by inserting the section 15' onto and over the section 16' until the condition shown in Fig. 8 is attained. The joint or crevice between the end of the section 15' and the end of the collar 21' may be sealed and closed by a strip of tape 39, or other suitable sealing medium applied thereto as shown.

The package as thus filled and sealed is in condition for vending, and it is especially suited for holding commodities such as lawn seed, pulverized fertilizer, sand, insecticide, disinfectant or the like, or in fact any powdered or granular commodity which it is desirable to spread over a given area by means of a spraying operation. In use the sealing medium 39 is removed as is the cap 38 which temporarily closes the discharge apertures 36, and then the container is operated in the manner of a pump to discharge the contents in spray form, in the manner shown in Fig. 7.

From the foregoing description it will be seen that with the present invention a suitable commodity can be originally packed in the container in a very convenient and expeditious manner without the necessity of special tools, equipment or appliances. When the commodity is thus packaged it is presented to the consumer in an attractive sealed manner, and the package is of such a nature that re-use or refilling of the same with an inferior or substitute commodity is precluded. In addition, the consumer can dispense the commodity directly from the container in a convenient spray or stream form under pressure, by using the container itself as a pumping or force impelling medium. The container is relatively inexpensive to manufacture, and after the contents have been exhausted therefrom it may be readily discarded and disposed of.

While the particular embodiments of the invention have been set forth for the purpose of description, it is not intended that the invention be limited precisely thereto, and all changes and modifications as are within the scope of the annexed claims are contemplated.

What is claimed as the invention is:

1. A dispensing container, comprising a pair of hollow tubular members, said members both being formed of paper board and being fitted together in telescopic relationship, the outer section being of less length than the inner section, a metal cap crimped to the outer end portion of the outer section and closing said end, a collar surrounding the outer end of the inner section, a metallic cap crimped to the outer end of said collar and closing the adjacent end of said inner section, said cap having a discharge opening therein, a temporary cover removably positioned over said latter cap, and a severable closing medium between said collar and the inner end of said outer section.

2. A dispensing container, comprising a pair of hollow tubular members, said members both being formed of paper board and being fitted together in telescopic relationship, a metal cap

crimped to the outer end portion of the outer section and closing said end, a paper board collar surrounding the outer end of the inner section and projecting slightly beyond the adjacent end 5 of said latter section forming an internal shoulder, and a rupturable metal cap crimped to the projecting portion of said collar and also seating on said internal shoulder, the outer section being of less length than the inner section and said inner section, in its innermost position having its 10 inner end firmly engaging the cap on the outer section.

3. A dispensing container, comprising a pair of hollow tubular members fitted together in tele-

scopic relationship, a closure cap secured to and closing the outer end of the outer section, a collar surrounding the outer end of the inner section and projecting slightly beyond the adjacent end of said latter section and forming an internal shoulder, a metallic channel member tightly embracing said shoulder, and a rupturable cap crimped to the projecting portion of said collar and also seating on said channel member, the outer section being of less length than the inner 10 section and said inner section, in its innermost position, having its inner end firmly engaging the cap on the outer section.

MILTON M. KARGER.
